UNITED STATES PATENT OFFICE.

THADDEUS STEPHENS CASNER, OF PLAINFIELD, NEW JERSEY, ASSIGNOR, BY MESNE ASSIGNMENTS, TO RADIO ELECTRIC CLOCK CORPORATION, OF NEW YORK, N. Y., A CORPORATION OF DELAWARE.

MECHANISM FOR SYNCHRONIZING CLOCKS.

Application filed March 24, 1921, Serial No. 455,262. Renewed February 5, 1925.

To all whom it may concern:

Be it known that I, THADDEUS STEPHENS CASNER, a citizen of the United States, and residing at Plainfield, Union County, State of New Jersey, have invented certain new and useful Improvements in Mechanism for Synchronizing Clocks, of which the following is a specification.

The present invention relates to mechanism for synchronizing clocks and particularly to electro-magnetic mechanism by means of which a clock may be periodically corrected by electrical impulses transmitted through space. These impulses are known 10 as Hertzian waves or vibrations and may be transmitted from the sending station for long distances at such a high rate of speed that the lapse of time between the instant of sending from the transmitting station, 15 and the instant of receiving at the receiving station, is negligible. Realizing the advantages of utilizing the Hertzian waves in transmitting a daily time signal throughout the United States with the end in view of 20 synchronizing the reference time pieces of the country, the United States Government now sends out daily at 12 o'clock noon and 10 o'clock at night a series of signals by wireless telegraph from a station adjacent 25 to the clock which is used as a standard time piece for all other time pieces of the country. It has been found necessary to send out, instead of a single signal upon the instant of 12 o'clock, a series of warning signals 30 which terminates in the final signal which indicates either noon or 10 o'clock at night, as the case may be. For instance, it is now the practice of the Government to begin sending such signals five minutes before 35 12 o'clock, such signals being sent daily in accordance with a definite prearranged code by means of which the operators at the receiving stations are apprised of the fact that the time signal is about to be given in 40 order that they may be fully prepared to receive it. In accordance with the present 45 code the first noon signal occurs at five minutes before 12 o'clock and signals are given at one second intervals until the final signal,

which is sent forth exactly at 12 o'clock. 50 The series of signals is broken, however, by intervals of silence so that the receivers may note the passing of the minutes and so they may also clearly distinguish the signal given at 12 o'clock from all other signals. For 55 this purpose the 29th second signal of each minute series is omitted and also the last five second-signals of each minute series are omitted for the first four minutes, but in the last minute series the 10 second-signals 60 immediately preceding the final noon signal are omitted to further distinguish this particular signal from all others.

It has heretofore been the practice of operators of wireless receiving stations through 65 the country to listen to the series of signals and to operate a stop watch upon the final signal, with which watch the other clocks may be manually synchronized. This involves not only the necessity of having an 70 expert wireless operator wherever accuracy of clocks is desired, but is hardly an accurate method inasmuch as the operator may not start his stop watch upon the exact instant of hearing the signal, and also the stop 75 watch itself may be inaccurate and the clocks which are to be corrected from the stop watch may not be accurately synchronized therewith by the person performing this function. Where electric clock systems are 80 utilized, involving as they do a master clock and a large number of secondary clocks all synchronized with the master clock, it is desirable that the system be corrected daily, 85 that is, that the master clock be corrected daily in order that the entire clock system may give accurate time indications. By such daily corrections the installation of a cumbersome and expensive master clock of great accuracy may be avoided but such 90 daily corrections by wireless have heretofore necessitated the presence of an experienced wireless expert, which involves a considerable expense where such expert is not also needed for other purposes. 95

The present invention provides means whereby a clock may be automatically corrected by the noon or night wireless sig-

nals of the Government, thereby enabling a clock of average cost and accuracy, which would ordinarily vary a few seconds in time each day, to give practically accurate time indications and without the necessity of having a wireless operator present. This electro-mechanical synchronizing mechanism may be installed in all buildings, such as office buildings, hotels, public buildings and 10 in private homes without great expense, involving the installation of only a standard wireless receiving set of any well known kind, the installation of a transmitting set being of course unnecessary.

15 It has heretofore been suggested that clocks may be synchronized through space by means of electrical impulses but such mechanisms have not been capable of accomplishing the objects of the present invention, 20 the problem of selecting the correct signal of the series of signals and automatically correcting a clock being vastly different from the problems solved by the prior inventors whose apparatus will either function upon receiving a single signal, whether 25 this signal is the proper one or not; or will function only when the signals are sent by a special transmitting apparatus. The problem of providing a mechanism for automatically 30 setting a clock by one of a series of similar signals, such as now sent out daily by the Government, has heretofore remained unsolved.

In the following description and in the 35 accompanying drawings I disclose one embodiment of my invention by way of example. It will be obvious that the device may be altered to suit different conditions and to become operative on receipt of different codes of signals and may be modified in various other ways within the scope of the invention, which is of broad character.

In the drawings:

Figure 1 is a view from the front of a 45 master clock having the correcting device incorporated therewith, the casing, dial, and hands having been omitted;

Figure 2 is a side view of the same;

Figure 3 is a section on the line 3—3 of 50 Figure 2, part of the clock mechanism having been broken away;

Figure 4 is a rear elevation, part being broken away;

Figure 5 is a section on the line 5—5 of 55 Figure 1;

Figure 6 is a sectional view through the aligned drive shaft and second hand shaft of the clock;

Figure 7 is a front elevation of a portion 60 of the mechanism illustrated in Figure 1, certain of the moving parts being shown in different positions;

Figure 8 is a section on the line 8—8 of 65 Figure 7;

Figure 9 is a section on the line 9—9 of

Figure 1 but showing a portion of a movable arm which is not present in that section;

Figure 10 is a similar view showing the movable arm in a different position;

Figure 11 is a section on the line 11—11 of Figure 1;

Figure 12 is a side view of a switch controlling the secondary clock circuits, showing in section the switch operating cam;

Figure 13 is an elevation of the same;

Figure 14 is a schematic view of the electro-mechanical clock correcting mechanism;

Figure 15 is a view of a portion of this mechanism in a different position;

Figure 16 is a view of a switch illustrated 80 in Figures 1 and 14 and showing the parts in a different position; and

Figure 17 is a diagrammatic view of a modified form of a portion of the electro-mechanical correcting mechanism.

The master clock with which my present invention has been incorporated is illustrated, described and claimed in my Patent No. 1,492,318, but the construction and operation of this clock will be herein briefly described 90 to permit a more ready understanding of the construction and operation of the combined mechanism.

Journalized in the parallel plates 10 and 11 of the clock frame are five parallel shafts 12, 13, 14, 15 and a composite shaft S. These shafts are substantially as illustrated in my prior application with the exception of shaft S which is considerably modified to aid in the accomplishment of the objects of the 100 present invention. The shaft 12 is the minute hand shaft, which has rotatably mounted thereon at its outer end the usual hour hand sleeve 16. The usual reducing gear R operatively connects the inner end 105 of the hour sleeve to the minute hand shaft, gear 17 being rigidly secured to the hour sleeve and pinion 18 being rigid on the shaft 12. Loosely mounted on the shaft 12 is a

large gear 19 having a sleeve 20, a spring 21 being provided for forcing the gear 19 against the pinion 18 for frictional engagement. This frictional engagement is sufficient for driving the hands while it permits the hands to be moved manually in setting the clock without necessitating the rotation of the gear 19 and the other gearing of the clock. Shaft 13 is an intermediate or idler shaft and has fixed thereon a pinion 22 meshing with the gear 19 and a gear 23 120 which meshes with a pinion 24.

The shaft 15 is an escapement shaft having at its rear or inner end a crank 25 the horizontal end portion 26 of which cooperates with a slotted plate 27 secured to the pendulum 28. Rotation of the shaft 15 causes the arm 26 to bear alternately on the vertical faces of slotted plate 27 to cause the oscillation of the pendulum. Rigid on the shaft 15 is a pinion 29 which meshes with a 130

gear 30 on shaft 14, which is a second idler shaft and has rigidly mounted thereon a pinion 31 which meshes with a large gear 32 on shaft S.

5 Referring particularly to Figure 6 it will be seen that the shaft S comprises two coaxial and relatively rotatable portions, the rear portion 33 having a reduced forwardly extending axial portion or spindle 34 which 10 is received within a correspondingly shaped axial recess in shaft 35. The gear 32 previously referred to is fixed on the forward end of the main portion of the shaft 33 and has secured concentrically thereto an annular 15 friction member 36 of angular cross section, the inner margin of which has its rearwardly directed face pressing against the outer face of a disk 37 which is fixed on the inner end of shaft 35. The degree of pressure exerted by friction member 36 on the disk 37 may be varied by adjusting screws 38.

The shaft 33 is the drive or power shaft of the clock and the shaft 35 is the second 20 hand supporting shaft and these shafts are normally operatively clutched together by the friction clutch just described, but when a torque is exerted on the shaft 35 to correct the position of the second hand the 25 clutch will slip, allowing the second hand shaft to be rotated independently of the drive shaft so that such friction will not interfere with the driving mechanism. As the hour and minute hand shafts are driven 30 by the pinion 24 which is fast on the shaft 35, and the pendulum is driven from the gear 32 which is fast on shaft 33, it is evident that the driving means, including the time measuring means or pendulum, is only 35 frictionally connected to the time indicating means, including the three hand-supporting shafts, and that when power is applied to one of the shafts to correct the positions of the several hands the driving mechanism 40 will be unaffected.

Shaft 33 is driven by means of a coiled spring *a* which has one end secured to the frame and its other end secured to an S-shaped armature *b* rotatably mounted on 45 shaft 33, this armature having a pawl *c* which cooperates with a ratchet wheel *d* fixed on shaft 33. A rocker *e*, pivotally secured to the frame has arms extending laterally above and below the shaft 33 and lying 50 in the path of a pin *f* secured to the armature *b*. As the spring unwinds armature *b* moves in a clockwise direction (Figure 3) until pin *f* strikes the upper arm of the 55 rocker, which then flies upwardly to close switch W, controlling the circuit through electro-magnet *g*. This magnet immediately acts to turn armature *b* to a vertical position during which movement the pin *f* strikes the lower arm of the rocker which snaps downwardly and opens switch W. This action,

which occurs about four times each minute, is more fully described in my copending application previously referred to.

Fixed on the shaft 35 is a disk 39 having a forwardly projecting pin 40, the axis of 70 which passes through the longitudinal axis of the second hand 41, that is, pin 40 and the second hand 41 bear the same angular relationship to the shaft 35. A cam 42 of insulating material of the shape clearly 75 shown in Figure 12 is fixed on the second hand shaft in front of the plate 11 and this cam closes the switch controlling the electrical circuits through the secondary clocks once each minute, so that the hands of such 80 secondary clocks will be advanced at the minute intervals. The secondary clock switch comprises spring contact blades 43 and 44 which are insulated from each other and from the frame, being secured at their 85 lower ends to an insulating block 45. The cam has a longitudinal radial face and as it rotates the ends of contacts 43 and 44 pass over the sharp edge of the cam once 90 each minute and move radially toward the 95 shaft 35. The blades 43 and 44 are, however, of unequal length and blade 44, being the shorter of the two blades, will fall about two seconds before the blade 43 thereby bringing the contact point 45 of blade 44 against contact point 46 of blade 43 and completing the circuit through the secondary clock system. As cam 42 continues its rotation, however, the blade 43 will move 100 relatively to the blade 44 and will separate the two contacts 45 and 46 breaking the circuit through the secondary clocks.

It will be apparent that if the angular position of the second hand shaft is changed that the angular position of the cam 42 105 will be simultaneously changed, and the timing of the secondary clocks changed exactly as the timing of the master clock.

The mechanism for correcting the position of the hands of the clock daily will now 110 be described. It will be observed in this connection that the average master clock will vary only a few seconds within 24 hours and I have therefore positioned the hand-correcting means to cooperate with the second hand of the clock in which position it will be effective to make corrections of errors as large as 20 or 25 seconds whether the clock be either fast or slow, but it will be understood that the correcting or synchronizing mechanism may be applied to an intermediate shaft or to the minute shaft as desired for the correction of greater errors. Pivotedly connected at 47 to a bracket 48 secured to the frame of the clock is a lever 49 115 extending transversely and parallel to the front plate 11, the free end of this lever being connected by means of a link 50 to the armature 51 of a solenoid electro-magnet 52 secured to the face plate 11. 120

This lever 49 lies directly below the pin 40 of the disk 39 and is provided with a slot 53, the sides of which are arcs of circles described about the pivotal axis 47 and which is adapted to receive, when the lever 49 is moved upwardly, both the second shaft 35 and the pin 40. The upper end of the slot 53 is open for this purpose and the upper edge of the lever has two inclined portions 54 adjacent the mouth of the slot for guiding the pin 40 into the slot when the lever is raised. The solenoid 52 is connected in an electrical circuit which includes a battery 55 and a control switch 66 having a fixed contact 67 and a movable contact 68 which is resilient and normally tends to remain out of contact with the fixed contact 67. Whenever, however, the spring contact 68 has been moved to close the switch the armature 51 will immediately move vertically upward thereby raising the lever 49 and moving the pin 40 to a position vertically above the second shaft 35, as the pin will ride down the inclined edge or cam 54 and enter the slot 53. This of course rotates the second hand shaft which will cause the hand 41 to assume its vertical or zero position, which position it should of course occupy at 12 o'clock noon at which time switch 66 is closed by mechanism now to be described.

It will be seen from Figures 4 and 14 that an insulating block 69 is secured to the resilient switch blade 68, this block having a raised portion at its upper end. A segmental member 70 is pivotally supported adjacent the switch 66 and is provided with a laterally extending pin 71, the path of rotation of which about the pivotal axis of member 70 passes through the raised portion of insulating member 69. When the member 70 is rotated in a counterclockwise direction (Figure 14), the pin 71 will strike the insulating block 69 and close the switch, and upon movement in the opposite direction will release the block and allow the switch to immediately open. A coiled spring 72 having one end connected to the stationary frame and the other end connected to the member 70 normally tends to keep the member 70 in the position shown in Figure 14 with the pin 71 adjacent block 69.

When rotated in a clockwise direction and released the member 70 will tend to close the switch and, if it has been rotated through a sufficient angle, the spring will impart to it sufficient energy for this purpose but the strength of the spring 72 is such that the member 70 will not have sufficient energy to close the switch unless it has been rotated through a rather wide angle and then released. It will be seen that one edge of member 70, that is, the edge opposite pin 71, is circular and is provided with eleven teeth 73. These teeth cooperate with a dog 74 pivoted to the frame of the machine and a pawl 75 which is vertically disposed and the lower end of which is pivoted to a lever 76. The outward movement of the dog 74 is limited by a stop 77 and it can move only between its full and dotted line positions, as shown in Figure 14. The pawl 75 is movable laterally between dog 74 and segment 70 and is also movable to a limited distance as indicated by the full and dotted line positions in Figure 14. The lever 76 to which the pawl 75 is pivoted, is pivoted at 78 to the armature 79 of a solenoid 80 secured to the frame of the machine, and is provided at its free end with a projection or boss 81 which extends upwardly and lies in the vertical plane of a roller 82 which is fastened to and extends laterally from the pendulum. When the pendulum is in its central position the roller 82 lies directly above the boss 81.

Normally the lever 76 rests upon a bracket 83 secured to the frame of the clock but when the solenoid 80 is energized, it will be raised, lifting pawl 75 and bringing the boss 81 into the path of the swinging roller 82. In its raised position spring 84 throws the upper end of the pawl into engagement with the uppermost tooth of the eleven teeth 73 and, as lever 76 is rocked by the roller 82 of the swinging pendulum once each second, the pawl 75 will be effective in rotating the toothed segment 70 one tooth per second. The dog 74 prevents return of member 70 under the influence of spring 72 and it will be obvious that in ten seconds the segmental member 70 will have been rotated through an angle equal to the angle subtended by ten consecutive teeth 73. Further rotation of segment 70 is impossible since there are no more teeth for pawl 75 to engage. If, after segment 70 has been rotated in this manner, dog 74 should be disengaged from the lowermost tooth 73 the segment will instantly rotate under the influence of spring 72 and close the switch 66. The spring is, however, of such a strength, as previously pointed out, that the segment will not have sufficient energy to close the switch unless it has been rotated at least nine of the ten teeth.

The means for opening switch 66 comprises a lever 85 pivoted to the frame of the clock and having at its free end an armature 86 and a laterally extending pin 87. The armature 86 is positioned to cooperate with the solenoid 80 so that when the latter is energized the lever will be drawn downwardly against the action of a leaf spring 88, and when the solenoid is deenergized this spring will move the lever upward until the pin 87 engages an inclined edge 89 of segment 70. This edge 89 acts as a cam and when it is struck by pin 87 the segment 70 is rotated through a sufficient angle in a clockwise direction to cause pin 130

71 to disengage block 69 and to allow switch 66 to open. When pawl 75 is acting to rotate segment 70, however, the pin 87 is held clear of 70 by the action of the solenoid 80.

The electro-magnet 80 is connected in circuit with a battery 90 and a switch indicated generally at 91. This switch, which comprises two resilient contact blades 92, 93, having suitable contact points at their lower ends is closed at approximately two minutes before the instant of noon each day. When the switch is closed the pawl 75 will of course be raised and the rotation of segment 70 will be begun. Secured to switch blade 92 is an insulating block 94 having at its lower end a small raised portion or bead 95 which lies in the path of a pin 96 mounted on an arm 97 which is secured to the hour sleeve so that it describes two complete revolutions in 24 hours. To prevent the switch 91 from being closed twice in a 24 hour period, however, means is provided for causing the pin 96 to miss the projection 95 upon one rotation of the arm 97. This means comprises a plate 98 having a circular opening 99 therein concentric with the axis of the hour sleeve and having also a gap 100 at the top, the ends of which are radial 30 and one of which is formed as a knife edge 101. Secured to the top of the plate 98 is a U-shaped member 102 having depending legs extending downwardly on opposite sides of the plate and opposite the gap 100. The inner surfaces of these legs are rounded, as clearly shown in Figures 9 and 10 and act as guides for the flexible circular extension 103 to arm 97. As this flexible extension 103 passes gap 100, as it does each 40 12 hours, it is guided from one side of the plate 98 to the other by member 102. In Figure 10 it is shown passing from the front side of the plate to the rear side and in Figure 9 from the rear side to the front side. Only when the arm 103 is on the front side of plate 98 can pin 96 engage the projection 95 as it passes block 94. This is clearly shown in Figure 8, and it will also be seen that pin 96 is extended through arm 50 97 and, when projection 103 is on the rear side of the plate, is in position to contact with, in its downward movement, an arm 104 which is rigid on an arbor 105 journaled in the plate. This arbor supports at its 55 forward end a substantially triangular cam member 106 which bears against the flexible contact 93.

In order that the switch 91 be closed it is necessary that cam 106 be set in the position shown in Figure 14 and that the pin 96 be in engagement with projection 95. This dual control of the switch is provided so that it may immediately be opened after the time correction has been made, and for this purpose arm 104 is provided with a

depending rod 107, the lower end of which lies in the path of the setting lever 49. As soon as the lever 49 is raised therefore, to set the clock, it opens the switch 91 by raising arm 104 thereby rotating cam 106. After arm 104 is raised in this manner it will remain in such position (Figure 7) until arm 97 has again moved it downwardly 12 hours later. It will be seen therefore that lever 76 is lifted into operative position between one and two minutes before the noon signal is expected and is dropped into inoperative position immediately after setting of the clock, and that switch 91 will be closed only at noon, and not 12 hours later or at midnight.

The mechanism above described will of course effect the setting of the hands approximately at the noon hour, that is, within a minute or two of noon and would not 85 operate again until the following noon, but such setting would be entirely inaccurate without the controlling devices therefor, now to be described.

It will be observed that in Figure 14 the pawl 75 has a wedge shaped member 108 secured thereto adjacent its lower end. This member not only comprises a cam, cooperating with the fixed stop 109 to throw the pawl 75 away from segment 70 as it falls and also to throw dog 74 out of engagement with the segment, but also constitutes an armature for electro-magnet 110, which is secured to the frame of the clock adjacent thereto. This electro-magnet is in circuit with the battery 111 and the armature 112 of an electro-magnet 114. A spring 113 normally tends to close the circuit through magnet 110. Electro-magnet 114 is however normally energized, and prevents the closing of this circuit except when deenergized. This electro-magnet 114 is in circuit with a battery 115 and a movable lever 116 which constitutes one member of a relay 100-105 adapted to act when energized by the faint impulses received from a wireless receiving apparatus, (not illustrated). This relay is fully described and claimed in my copending application Serial Number 455,261, filed 110 March 24, 1921, and will herein be only 115 briefly described.

The lever 116 is pivoted on a knife edge 117 and a spring 118 normally tends to rotate it about its pivotal axis so that its opposite end will disengage the adjustable contact 119. An adjustable screw will disengage the adjustable contact 119. An adjustable screw 120 extends laterally from the lever 116 at its quarter point and the end of this screw abuts against a soft rubber sleeve 121 which covers the end of a second and parallel lever 122. The lever 122 has its opposite end pivotally mounted upon a knife edge 123 and a spring 124 tends to rotate 125 this lever about its pivotal axis, maintaining 130

it in contact with a projection 125 on the vibratory diaphragm 126 of a telephone receiver 127. Wires 128 connect receiver 127, which may be of any well known type such as the Brandes receiver, to wireless receiving apparatus which may also be of well known type, for instance the De Forest receiving set. The circuit through battery 115 and magnet 114 is normally closed but when diaphragm 126 is caused to vibrate, due to the reception of a signal from the wireless receiving set, the lever 116 is thrown away from contact 119, thereby opening the circuit. Magnet 114 is immediately deenergized and spring 113 acts to close the circuit through magnet 110 which in turn attracts armature 108. This attraction of armature 108 therefore occurs each time a signal is received which, in taking the time signals at noon, will be once each second. Not only is pawl 75 moved from segment 70 at each such signal but also dog 74 will be moved to disengage the segment.

It will be seen therefore that the mechanism just described, which includes the relay electro-magnet 114, tends to nullify the action of the previously described apparatus for closing switch 66. That is, after the switch 91 has been closed at approximately two minutes before noon and pawl 75 has been thrown into operative position to wind spring 72, by energy imparted by the pendulum of the clock at second intervals, the magnet 110 will act at second intervals to prevent the completion of the necessary winding movement by the pawl. So long as the impulses are received by the receiving apparatus, the pawl 75 cannot accomplish the winding, but when the signals stop, the pawl 75 will be effective. For instance, as no signal is received by the wireless set at the 29th second, the pawl will be able to advance the segment one tooth, but this advance will be lost with the arrival of the 30th second since magnet 110 will again draw pawl 75 and dog 74 out of engagement with teeth 73. As the 55th through the 59th seconds are omitted from the wireless code the pawl will gain five teeth at the end of the minute but, upon the 60th second, the pawl and dog 74 will again be drawn out of operative position and the segment 80 will fly back to zero position but without sufficient force however to operate the switch 66.

At the end of the minute immediately preceding the noon signal ten wireless signals are omitted and in these ten seconds pawl 75 is enabled to advance segment 70 ten teeth, in cooperation with dog 74. When the final or noon signal is received however the pawl and dog are again thrown into inoperative position and segment 70 rotates and acquires sufficient energy to close the switch 66, whereupon the lever 49 is immediately raised and the hands of the clock

corrected. Movement of the lever 49 causes the switch 91 to open (Figure 16), armature 86 is released and lever 85 becomes operative to move segment 70 to open the switch 66 so that the lever 49 again may immediately drop so as to avoid impeding the progress of the second hand. When magnet 80 is de-energized the pawl 75 is of course thrown to inoperative position by cam 108, as well as dog 74, so that the movement of segment 70 is not interfered with. The action will not be repeated for 24 hours or until arm 104, which has just been raised, has again been moved downwardly to advance switch blade 93, and until the pin 96 has again come in contact with the projection 95 to close the switch 91.

This switch 91 is therefore a period switch called into operation at intervals of 24 hours. The segment 70 together with its spring 72 constitute in reality a spring motor in which energy is stored until the proper instant, when it is released to close the switch controlling the hand setting lever.

In Figure 17 is illustrated a modified form of mechanism for operatively connecting the pendulum to the segment 70. Here the pendulum is connected in circuit with a battery 150 and an electro-magnet 151, the pin 152 of the pendulum constituting the moving contact of the switch controlling this circuit and the flexible blade 153 constituting the stationary contact. Normally the contacts are separated as shown, but when switch 91 is closed electro-magnet 151 is energized and blade 153 raised so that it lies in the path of pin 152, thus causing a contact once each second. Magnet 151 is energized therefore at second intervals and acts to rock lever 155 at each energization thereof, to advance the segment 70. In some cases this form of operating mechanism will be preferred to the form illustrated in the other figures of the drawings.

It will be apparent to one skilled in the art that the elements and component parts of the invention may be differently arranged and greatly modified. The invention is not limited therefore in its scope to the embodiment disclosed.

Having thus described the invention what I claim as new and desire to secure by Letters Patent is:

1. A clock including in combination, a drive shaft, a driven shaft, time indicating hand shafts moved by said driven shaft, means for driving said drive shaft, and friction means connecting said shafts for simultaneous rotation, said means comprising two discs one secured on each of said shafts, and a friction member secured to one of said discs and frictionally engaging the other.
2. A clock including in combination, a drive shaft, a driven shaft coaxial there-

with, time indicating hand shafts moved by said driven shaft means for rotating said drive shaft, and friction means connecting said shafts for simultaneous rotation comprising two discs having contiguous faces and one being connected to each of said shafts, and a friction member secured to one of said discs and engaging the other.

3. A clock including in combination; a drive shaft, means for rotating said shaft at uniform speed, a second hand shaft, hour and minute hand shafts geared to said second hand shaft, and a friction device for connecting said drive shaft to said second hand shaft whereby the hand shafts may be simultaneously adjusted relatively to the drive shaft.

4. A clock including in combination, a drive shaft, a clock train, hand shafts connected to said train and adapted to be operated thereby and a friction device operatively connecting said train and power shaft whereby the train may be adjusted independently of the drive shaft.

5. A clock including in combination, a drive shaft, hour, minute and second indicating hand shafts, and means connecting said hand shafts to said drive shaft whereby the hand shafts may be operated, said means including a single clutch through which motion of the shaft is transmitted to each of the hand shafts and whereby the hand shafts may be adjusted relatively to the drive shaft.

6. A clock including in combination, a drive shaft, a second hand shaft, hour and minute hand shafts, a gear train operatively connecting said shafts, and a single clutch directly connecting the drive shaft and second hand shaft and also connecting the drive shaft to the hour and minute shafts through the gear train.

7. In the automatic correction of a clock by recurrent electrical impulses separated by time intervals of different lengths through the medium of electrically actuated mechanism, the method of selecting an impulse following a relatively long interval between impulses which comprises arranging said mechanism so as to tend to change its condition during the time that impulses are being received, but to actually change to a certain condition only in the absence of recurrent electrical impulses during a predetermined period, and employing one of said impulses to actuate said mechanism when said change has occurred.

8. A system for automatically correcting a clock by radio signals, which comprises a radio receiver, an electro-magnetic device actuated synchronously with current impulses delivered by said radio receiver, selecting mechanism operated by said electro-magnetic device and time controlled, in such manner that effective actuation there-

of is brought about only by a current impulse separated by an interval of predetermined minimum length from the next preceding impulse, a control switch closed by said selecting mechanism, a second electro-magnetic device connected through said control switch to a local source of power, a movable member adapted to set said clock and operated by said second electro-magnetic device and a clock operated switch adapted to cause the system to function only at times of day when radio signals are normally transmitted.

9. Mechanism for periodically correcting the angular position of a rotatable clock shaft comprising in combination, a member movable relatively to the shaft for rotating the same, electromagnetic means including a control switch for operating said member, and means for effecting the closure of said control switch at a predetermined instant said means including a second switch and a device for closing said second switch once in twenty four hours.

10. Mechanism for periodically correcting the angular position of a rotatable clock shaft comprising in combination, a member movable relatively to the shaft for rotating the same, electromagnetic means including a control switch for operating said member and a device for effecting the closure of said control switch at a predetermined instant said device including a second switch and an element for closing said second switch, said element being adapted to be mounted on the hour shaft of a clock and rotatable therewith and having guiding means to bring it into contact with said second switch.

11. Mechanism for periodically correcting the angular position of a rotatable clock shaft comprising in combination, a member movable relatively to the shaft for rotating the same, electromagnetic means including a control switch, for operating said member, means for effecting the closure of said control switch at a predetermined instant, said means including a second switch having a device for closing said second switch and a device for opening said second switch immediately upon the movement of the first mentioned member.

12. Mechanism for periodically correcting the angular position of a rotatable clock shaft comprising in combination, a member movable relatively to the shaft for rotating the same, electromagnetic means including a control switch, for operating said member, means for effecting the closure of said control switch at a predetermined instant, said means including a second switch having a device for closing said second switch, cam means for opening the second switch immediately upon the movement of said first mentioned member.

13. Mechanism for periodically correcting the angular position of a rotatable clock shaft comprising in combination, a member movable relatively to the shaft for rotating the same, electromagnetic means including a control switch for operating said member, means for effecting the closure of said control switch at a predetermined instant, said means including a second switch and a device for closing said second switch, and means adapted to be directly operated by said first mentioned member for opening the second switch.
14. Mechanism for periodically correcting the angular position of a rotatable clock shaft comprising in combination, a member movable relatively to the shaft for rotating the same, electromagnetic means including a control switch, for operating said member, means for effecting the closure of said control switch at a predetermined instant, said means including a second switch and a device for closing said second switch, and means for opening said second switch immediately upon the movement of said member, said second switch having a cam, an element connected to the cam and lying in the path of movement of said member.
15. Mechanism for periodically correcting the angular position of a rotatable shaft comprising in combination, a member movable relatively to the shaft for rotating the same, electromagnetic means for operating said member having a control switch, and a device for closing the control switch which includes a member adapted to be operated by a clock pendulum.
16. Mechanism for periodically correcting the angular position of a rotatable clock shaft comprising in combination, a member movable relatively to the shaft for rotating the same, electromagnetic means for operating said member having a control switch, and a device for closing the control switch which includes a member adapted to be operated by a clock pendulum but normally in inoperative position, and means for moving said member into position to be engaged by said pendulum, prior to the operation of said control switch.
17. Mechanism for periodically correcting the angular position of a rotatable shaft comprising in combination, a member movable relatively to the shaft for rotating the same, electromagnetic means for operating said member, having a control switch and a device for closing the control switch which includes a member adapted to be operated by a clock pendulum, said member being provided with electromagnetic means for moving the same into position to be engaged by the pendulum.
18. Mechanism for periodically correcting the angular position of a rotatable clock shaft comprising in combination, a member movable relatively to the shaft for rotating the same, electromagnetic means for operating said member, having a control switch, and a device for closing the control switch which includes a lever pivotally mounted on the armature of a magnet one end of the lever being adapted to be engaged by the pendulum, and the armature and lever being moved into position such that the lever is engaged by the pendulum, when said magnet is energized.
19. An electrical system for controlling apparatus in accordance with a code of electrical impulses, including in combination, a movable member, clock controlled means operating only during a fraction of the twenty-four hour period when the impulses are being transmitted and adapted during a predetermined interval between impulses to move said member from an initial position to a position wherein it is effective to control said apparatus, and means for returning said member to its initial position upon the reception of each impulse, whereby the apparatus is controlled only upon a predetermined interval between successive impulses.
20. A selective system responsive to a code of electrical impulses, including in combination, a rotatable member biased to an initial position, clock controlled means operating only during a fraction of the twenty-four hour period when the impulses are being transmitted and adapted during a predetermined interval to move said member from its initial position to a position wherein it is effective to control means for giving an indication, and means responsive to the impulses for releasing said member and permitting it to return to initial position upon the reception of each impulse, whereby the indication is given only upon a predetermined interval between successive impulses.
21. An electrical system for indicating time in accordance with a code of impulses including, in combination, a movable member, means constantly tending during the time the impulses are being transmitted to move said member from an initial position to a position wherein it is effective to control means for giving a time indication, and means responsive to the impulses for returning said member to its initial position upon the reception of each impulse.
22. An electrical system for indicating time in accordance with a code of impulses including, in combination, clock controlled mechanism constantly operating only during a fraction of the twenty four hour period when the impulses are being transmitted and effective when operated a predetermined degree from an initial condition to control means for giving a time indication, and means for restoring said

mechanism to its initial condition upon the reception of each impulse.

23. An electrical system for indicating time in accordance with a code of electrical impulses including, in combination, time indicating means, impulse mechanism controlling said means, means constantly operating said impulse mechanism during the time the electrical impulses are being transmitted, said impulse mechanism being effective to control said time indicating means only after it has been operated a predetermined degree from a certain condition, and means for restoring said impulse mechanism to said condition upon the reception of each impulse.

24. A selective system for controlling apparatus in accordance with a code of electrical impulses including, in combination, impulse mechanism, clock controlled means for operating said impulse mechanism only during a fraction of the twenty-four hour period when the electrical impulses are being transmitted, said impulse mechanism being effective to control said apparatus only after it has been moved a predetermined extent from its initial position, and means for returning said impulse mechanism to its initial position upon the reception of each electrical impulse.

25. A selective system for controlling apparatus in accordance with a code of electrical impulses including, in combination, time indicating means comprising an electro-magnet, a normally open switch adapted to close the circuit of said electro-magnet, means for closing said switch including step-by-step-mechanism biased to an initial position and effective to close the switch only after being operated a predetermined number of steps from its initial position, and means responsive to the electrical impulses for restoring said step-by-step mechanism to its initial position upon the reception of each impulse.

26. An electrical system for indicating time in accordance with a code of electrical impulses including, in combination, a rotatable member biased to an initial position, clock controlled means constantly tending during the time the electrical impulses are being transmitted to move said member from its initial position to a position wherein it is effective when released to give a time indication, and means responsive to the electrical impulses for releasing said member upon the reception of each impulse, whereby the time indication is given only at the termination of a predetermined hiatus in the electrical impulses.

27. A selective system for controlling apparatus in accordance with a code of electrical impulses, in combination, means including an electro-magnet for controlling the apparatus, impulse mechanism control-

ling said electro-magnet, means controlled by the clock for operating said impulse mechanism during the time the electrical impulses are being transmitted, and means for restoring said impulse mechanism to its initial condition upon the reception of each electrical impulse, said impulse mechanism being effective to control said electro-magnet only after it has been operated a predetermined degree from its initial condition.

28. A system for setting a clock in response to a code of electrical impulses, in combination, impulse mechanism controlling the setting of the clock, clock controlled means constantly operating said impulse mechanism only during a fraction of the twenty-four hour period when the electrical impulses are being transmitted, said impulse mechanism being effective to set the clock only after it has been operated a predetermined degree from its initial position, and means for returning said impulse mechanism to initial position upon the reception of each impulse.

29. A system for setting a clock in accordance with a code of electrical impulses, in combination, time controlled means operating during the transmission of impulses, means for setting the clock upon the reception of a signal impulse if, and only if, said time controlled means has operated a predetermined extent from a certain condition, and means for preventing said time controlled means from attaining said predetermined extent of operation so long as the signal impulses are received at predetermined intervals apart.

30. A system for setting a clock in accordance with a code of electrical impulses, in combination, time controlled means automatically set in operation approximately at the beginning of the time signal impulses, means for setting the clock upon the reception of a signal impulse if, and only if, said time controlled means has attained a predetermined extent of operation with respect to a certain condition, means for preventing said time controlled means from attaining said predetermined extent of operation so long as the signal impulses are received at predetermined intervals apart, and automatic means for discontinuing the operation of said time controlled means when the clock is set.

31. A selective system for controlling apparatus in accordance with a code of electrical impulses, including, in combination, time controlled means set in operation approximately at the beginning of the transmission of impulses and effective to control the apparatus only after having been operated a predetermined degree from its initial condition, and means to restore said time controlled means to its initial condition upon the reception of each electrical impulse.

32. A system for setting a clock in accordance with a code of electrical impulses including, in combination, mechanism operated by the clock and constantly tending to move to a position wherein it is effective to set the clock, said mechanism being set in operation approximately at the beginning of the transmission of impulses, and means responsive to the electrical impulses to restore said mechanism to its initial position upon the reception of each impulse. 70
33. A system for setting a clock in accordance with a code of electrical impulses, including, in combination, mechanism adapted when uninterruptedly operated for a certain interval of time to attain a condition in which it is effective to set the clock, means for setting said mechanism in operation approximately at the beginning of the time signal transmission and means for restoring said mechanism to its initial condition upon the reception of each signal impulse. 75
34. A selective system for controlling apparatus in accordance with a code of electrical impulses, including, in combination, mechanism adapted when uninterruptedly operated for a certain interval of time to attain a condition in which it is effective to control said apparatus, means for setting said mechanism in operation approximately at the beginning of the transmission of the electrical impulses, and means for restoring said mechanism to its initial condition upon the reception of each signal impulse. 80
35. A system for setting a clock in accordance with a code of electrical impulses, including, in combination, mechanism adapted when uninterruptedly operated for a certain interval of time to attain a condition in which it is effective to set the clock, means for setting said mechanism in operation approximately at the beginning of the transmission of impulses, means for restoring said mechanism to its initial condition upon the reception of each impulse, and means to discontinue the operation of said mechanism when the clock is set. 85
36. A system for setting a clock in accordance with a code of electrical impulses, including, in combination, time controlled means set in operation approximately at the beginning of the transmission of impulses, means for setting the clock only after said time controlled means has operated a predetermined degree from an initial condition and a signal impulse is received, means for restoring said time controlled means to initial condition upon the reception of each impulse, and means for discontinuing the operation of said time controlled means when the clock is set. 90
37. A selective system for controlling apparatus in response to a code of electrical impulses, including, in combination, means for controlling the apparatus, step-by-step mechanism controlled by the clock adapted to render said means operative to control the apparatus on movement through a predetermined number of steps, and an electromagnet controlled by the electrical impulses governing said mechanism and preventing effective movement thereof so long as the impulses are being received at predetermined intervals. 95
38. In a system for indicating time in accordance with a code of electrical impulses, time controlled means automatically set in operation near the beginning of the transmission of impulses, means for giving a time indication upon the reception of an impulse if, and only if, said time controlled means has operated a predetermined extent with respect to an initial condition, and means for preventing said time controlled means from attaining said predetermined extent of operation so long as the impulses are received at predetermined intervals apart. 100
39. In a system for setting a clock in accordance with a code of electrical impulses, in combination, normally inoperative step-by-step mechanism adapted to be operated by the clock, means controlled by the clock for rendering said mechanism operative approximately at the beginning of the transmission of impulses, means for setting the clock upon the reception of a signal impulse if, and only if, said step-by-step mechanism has been operated through a predetermined number of steps from its initial position, means for preventing said mechanism from attaining said predetermined extent of operation so long as the signals are received at predetermined intervals apart, and automatic means for discontinuing the operation of said step-by-step mechanism when the clock is set. 105
40. A selective system for closing a switch in response to a code of electrical impulses including, in combination, normally inactive power operated means effective when operated through a predetermined phase to close the switch, means independent of the impulses for initiating the operation of said first mentioned means and means responsive to the impulses for controlling said first mentioned means. 110
41. A selective system responsive to a code of electrical impulses including, in combination, a changeable medium, means for causing said medium to change during intervals between impulses, means controlled by said medium for giving an indication upon the reception of an impulse if, and only if, said medium has changed a predetermined degree from a certain condition, and means responsive to the impulses for preventing said medium from attaining said predetermined degree of change so long as the impulses are received at predetermined intervals, whereby the indication is given only upon a pre- 115

determined interval between successive impulses.

42. In a system for setting a clock in response to a code of signals, means for setting the clock including an electro-magnet, a control switch therefor, mechanism for setting the switch after a predetermined interval in a series of electrical impulses and an electro-magnet controlled by the signals governing said mechanism so as to prevent it from setting the switch so long as the signals are being received at shorter intervals.

In testimony whereof I hereunto affix my signature.

THADDEUS STEPHENS CASNER.
